UNITED STATES PATENT OFFICE.

JAMES PETER DONOVAN, OF GEORGETOWN, KENTUCKY.

MOLD FOR CONCRETE POSTS.

No. 851,503.

Specification of Letters Patent.

Patented April 23, 1907.

Application filed April 9, 1906. Serial No. 310,671.

To all whom it may concern:

Be it known that I, JAMES PETER DONOVAN, a citizen of the United States, and a resident of Georgetown, in the county of 5 Scott and State of Kentucky, have invented a new and Improved Mold for Concrete Posts, of which the following is a full, clear, and exact description.

The object of the invention is to provide a 10 new and improved mold for making concrete posts such as are more especially used in the construction of fences, the mold being simple and durable in construction and arranged to permit the production of posts in 15 an economical manner, the posts combining strength with lightness, and not likely to warp or crack.

The invention consists of novel features 20 and parts and combinations of the same which will be more fully described herein-after and then pointed out in the claims.

A practical embodiment of the invention 25 is represented in the accompanying drawings forming a part of this specification, in which similar characters of reference indicate corresponding parts in all the views.

Figure 1 is a plan view of the improvement; Fig. 2 is a side elevation of the same; Fig. 3 is a sectional plan view of the same on the 30 line 3—3 of Fig. 2. Fig. 4 is a longitudinal sectional side elevation of the improvement on the line 4—4 of Fig. 1; Fig. 5 is a similar view of the same on the line 5—5 of Fig. 3; Fig. 6 is a transverse section of the improvement 35 on the line 6—6 of Fig. 3; Fig. 7 is a similar view of the same on the line 7—7 of Fig. 3; Figs. 8 and 9 are perspective views of the end blocks of the mold; Fig. 10 is an enlarged sectional side elevation of one of the 40 core-holding bolts; Fig. 11 is a perspective view of the reinforced concrete post made by the mold; and Fig. 12 is a perspective view of a portion of one of the reinforcing rods.

The sides A and A' of the mold are held 45 spaced apart by end blocks B and B' removably fastened in place by transverse bolts C extending through the sides A, A' and the end blocks B, B', as will be readily understood by reference to Fig. 3. The inner 50 face of the end blocks B (see Fig. 8), is formed with a tapering offset B², and the inner face of the other end block B' is provided with a sunken or a recessed panel B³, as shown in Fig. 9. Cores D are set in a space 55 between the sides A, A' and spaced apart, as

shown in Fig. 3, and in order to properly hold the cores D in position transversely extending core-holding bolts E are employed, engaging the sides A, A', each of the said bolts E being made in sections and having a rod E', (see Fig. 10) provided with sleeves E² and E³, of which the sleeve E² is secured to the rod E' and the sleeve E³ screws in a nut E⁴, which also screws onto the outer threaded end of the rod E'. The 60 sleeves E² and E³ are of such a length that the inner ends are spaced from each other, and the said inner ends of the sleeves E² and E³ abut against opposite faces of the core D, to hold the latter in proper position between the 65 sides A and A'. When it is desired to remove the cores D, as hereinafter more fully described, then the nuts E⁴ are unscrewed to allow of removing the sections of the bolts E from the mold and the post formed in the 70 mold. Each core D is provided at the top with a handle D', adapted to be taken hold of by an operator for conveniently pulling the core D out of the mold.

Through the sides A, A' and through the 75 cores D, also extend removable transverse rods F (see Fig. 3), and between the sides A and A' at the top thereof, fits a board G having openings G' in alignment with the upper ends of the cores D, to allow removal of the 80 latter through the said openings G' after the post is formed in the same.

The post H formed in the mold is provided with cover openings H', extending from side to side, and the post is also provided with 85 transverse apertures H² adapted to be engaged by the fence rails to hold the same in place on the post. The lower end of the post H is formed with a beveled offset H³ (see Fig. 4) owing to the panel B³ in the end block B', 90 and in the upper end of the post H is formed a recess or a sunken panel H⁴ owing to the offset B² formed on the end block B. The front end and rear sides of the post H are provided near their upper ends with recesses 95 or sunken panels H⁵ owing to offsets A² and A³, formed in the inner faces of the sides A, A', as plainly indicated in Fig. 3. The post H is reinforced in the direction of its length 100 by metallic reinforcing bars I and I' provided at their ends with anchoring heads I² preferably in the form of flat disks (see Fig. 12), for holding the reinforcing bars against 105 movement in the concrete material.

In using the mold the connected sides A, 110

A' , and blocks B, B' , are placed on a suitable smooth surface, preferably on oiled paper, to prevent sticking of the concrete material. The lower reinforcing bars I are then placed 5 in the mold and rest on the paper, after which the cores D are inserted and secured in position by the bolts E . The operator now places concrete material into the mold say to the depth of about one inch, and then raises 10 the reinforcing bars I through this layer of concrete material to the top thereof and preferably by the use of suitable hooks or other tools temporarily engaged with the rods I . When this has been done, more concrete 15 material is placed into the mold so as to embed the bars I , and when the mold is nearly filled the second set of bars I' is placed in position and then the mold is completely filled with cement material so that the bars 20 I' are also embedded in the material. When the mold is completely filled with cement material, the board G is placed in position on the top of the concrete material and then the board is pressed down to insure firm tamping 25 of the material in the mold. After the concrete material is set, the bolts E , as well as the rods F , are removed and then the cores D are withdrawn up through the openings G' in the board G , so that the concrete material is not 30 disturbed on the withdrawal of the cores D , as the walls of the openings G' form firm guides for the cores D during their withdrawal. After the cores have been withdrawn, the board G is removed and then the 35 bolts C are disengaged from the sides A, A' and the end blocks B, B' , to allow of removing the sides A, A' , as well as the end blocks B, B' .

From the foregoing it will be seen that the 40 mold is composed of comparatively few parts, which can be readily assembled for receiving the concrete material, and can be readily removed after the concrete material is set and the post is finished. It will also be noticed that by the arrangement described 45 suitable tying apertures H^2 are formed in the post, and having the cover openings H' the post is rendered comparatively light, without reducing the strength thereof. By having 50 the offset H^3 at the bottom of the post, the latter is not likely to turn in the post hole, and by providing the upper end of the post with panels H^5 , a highly ornamental appearance is given to the post.

Having thus described my invention, I claim as new and desire to secure by Letters Patent:

1. A mold for making concrete posts, comprising sides, end blocks for spacing the sides, 60 transverse bolts for connecting the end blocks with the said sides, cores set in the space between the sides, core-holding bolts engaging the said sides and cores, to hold the latter in position, and removable transverse 65 core rods arranged at opposite sides of the

core-holding bolts and extending through the sides and cores, to form apertures in the post for the attachment of the fence wires.

2. A mold for making concrete posts, comprising sides, end blocks for spacing the sides, 70 one of the end blocks having its inner face recessed and the other having its inner face provided with an offset, transverse bolts for connecting the end blocks with the said sides, cores set in the space between the sides, and core-holding bolts extending transversely through the sides and cores and provided with means for engaging the sides of the cores to hold the cores in position. 75

3. A mold for making concrete posts, comprising sides, end blocks for spacing the sides, the inner faces of the sides being provided with longitudinally extending rectangular offsets having beveled edges, one of the said end blocks having its inner face provided 80 with a rectangular recess or panel having beveled edges, and the other end block having its inner face provided with a rectangular offset having beveled edges, means for connecting the end blocks with the sides, 85 cores set in the space between the sides, and core-holding bolts extending transversely through the sides and cores and provided with means for engaging the sides of the cores to hold the latter in position. 90

4. A mold for making concrete posts, comprising sides, end blocks for spacing the sides, transverse bolts for connecting the end blocks with the said sides, cores set in the space between the sides, and core-holding bolts engaging the said sides and cores, to hold the latter in position, the said core-holding bolts being made in sections and having a reduced portion extending through the cores and shoulders abutting against the 105 sides of the cores. 95

5. In a mold, sides, end blocks, a core set in the space between the sides, and a core-holding bolt engaging the sides, the said bolt comprising a rod extending through the core, and spaced sleeves on the rod having their inner ends abutting against opposite faces of the core. 110

6. A mold for making concrete posts, comprising sides, end blocks for spacing the sides, 115 means for connecting the end blocks with the said sides, cores set in the space between the sides, core rods extending through the sides and cores to form apertures in the post, core-holding bolts engaging the said sides and cores, to hold the latter in position, the said core-holding bolts being made in sections and having a reduced portion extending through the cores and shoulders abutting against the sides of the cores, and a tamping board fitting between the sides and having openings for the removal of said cores. 120

7. A mold comprising sides, end blocks for spacing the sides, means for connecting the end blocks with the sides, cores set in the 125

space between the sides, core-holding bolts engaging the said sides and cores, the said core-holding bolts each consisting of a rod extending through a core, and spaced sleeves on the rod having their inner ends abutting against opposite faces of the core, and a tamping board fitted between the sides and having openings for the removal of the said cores.

10 8. In a mold, sides, end blocks, a core set in the space between the sides, and a core-holding bolt for holding the core in position, the said bolt comprising a rod extending through the core, spaced sleeves on the rod,

the said sleeves extending through the sides 15 and having their inner ends abutting against opposite faces of the core, one of said sleeves being secured to the rod, and a nut in which the outer end of the other sleeve screws, the said nut screwing on the end of the rod. 20

In testimony whereof I have signed my name to this specification in the presence of two subscribing witnesses.

JAMES PETER DONOVAN.
